WATER TUBE CONNECTION

Filed August 27, 1925

UNITED STATES PATENT OFFICE.

JOHN F. MOCK, OF PHILLIPSBURG, NEW JERSEY, ASSIGNOR TO INGERSOLL-RAND COMPANY, OF JERSEY CITY, NEW JERSEY, A CORPORATION OF NEW JERSEY.

WATER-TUBE CONNECTION.

Application filed August 27, 1925. Serial No. 52,951.

This invention relates to rock drills, but more particularly to a water tube connection for fluid actuated rock drills of the hammer type.

5 The objects of the invention are to prevent leakage of water from the back head into the cylinder of the drill, to prevent wear between the water tube and its seat and to eliminate the necessity of frequent inspection of the water tube and associated parts.

10 Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in which—

15 Figure 1 is an elevation, partly in section, of a rock drill equipped with a water tube connection constructed in accordance with the practice of the invention, and

20 Figure 2 is an enlarged detail view of a portion of the back head and the water tube connection.

25 Referring to the drawings, the invention is shown embodied in a drill having a cylinder A, a front head B and a back head C, which parts comprise the casing of the drill and are held in operative position by a pair of side bolts D, only a portion of one of which is shown, arranged on opposite sides of the drill. The cylinder A is provided 30 with a hammer piston E, only the nose of which is shown, for delivering blows on a hollow drill steel F supported by a chuck G in the front head B.

35 Pressure fluid for operating the drill is 40 conveyed through a suitable connection H which in this instance is secured to a valve chest J bolted to the cylinder A as by means of bolts K. A distribution valve (not shown) of any suitable type may be arranged in a valve chest J for distributing the pressure fluid to the opposite ends of the cylinder A to reciprocate the piston E.

45 In accordance with the practice of the invention, a recess L is formed in the back head C to receive a water tube O. The water tube O in this instance is provided with a bulb P near one end and extends through the cylinder A and the piston E into the rearward end of the drill steel F 50 for the purpose of conveying cleansing

liquid, such as water, to the drill steel for removing the cuttings from the drilled hole.

To the end that the recess L may be properly sealed against leakage of water therefrom a water plug Q is screwed into said 60 recess and has a bore R to receive the end of the water tube O. The inner end of the bore R terminates in a tapered seat S which cooperates with the bulb P of the tube O to form a fluid tight joint therebetween. If 65 desired, a gasket T of any suitable material may be compressed between the shoulder U of the water plug Q and the back head C to insure perfect sealing.

In order to prevent undue wear on the 70 bulb P when the water plug Q is screwed in position and such wear as may be caused by vibration set up in the drill during its operation, a disk V slideable in the recess L encircles the tube O and forms a seat for 75 the bulb P. In order to more thoroughly prevent leakage of water along the tube into the cylinder A, a packing W of any suitable compressible material, such as rubber, is arranged about the tube O and beneath the disk V, and is preferably provided with a washer X which acts as a seat for one end of a compression spring Y seated with its other end on the bottom of the recess L for holding the disk V firmly against 80 the bulb P and for compressing the packing W.

In this instance, an annular groove Z is 85 formed around the outside of the water plug Q and communicates with the bore R of 90 said tube through transverse passages b and also communicates with a water connection c, screwed in the back head or otherwise secured thereto, through a passage d.

95 From the foregoing description, it will be seen that the water tube is effectively sealed to prevent leakage of water therefrom into the percussive element of the drill, and that any wear which may take place between the bulb P and its seat will be automatically compensated for by the compressive action of the spring Y. By this form 100 of construction the water tube and its associated parts may be assembled in the back head and the proper adjustments made at the time the drill is assembled and thereafter 105 will require no more attention on the part of the operator.

I claim:

110 1. In a fluid actuated rock drill, the com-

bination of a cylinder and a back head, a recess in the back head, a water tube extending through the cylinder and into the recess, a bulb near one end of the tube, a disk 5 slideable in the recess forming a seat for the bulb, a compressible packing encircling the tube beneath the disk, a spring between the packing and the bottom of the recess for automatically compressing the packing and 20 for forcing the disk firmly against the bulb, a water plug to receive one end of the tube, and a shoulder on the water tube to cooperate with an end of the back head for sealing the recess. 25

10 to cooperate with the back head for limiting inward movement of the water plug with respect to the back head, and a spring beneath the disk for holding the disk firmly against the bulb and for holding the tube 30 yieldably in the water plug.

2. In a fluid actuated rock drill, the combination of a cylinder and a back head, a

recess in the back head, a water tube in the recess and extending through the cylinder, a bulb near one end of the tube, a disk slideable in the recess forming a seat for the bulb, a compressible packing encircling the tube beneath the disk, a spring between the packing and the bottom of the recess for automatically compressing the packing and 25 for forcing the disk firmly against the bulb, a water plug to receive one end of the tube, and a shoulder on the water tube to cooperate with an end of the back head for sealing the recess. 30

In testimony whereof I have signed this specification.

JOHN F. MOCK.
